UNITED STATES PATENT OFFICE.

ISRAEL L. LANDIS, OF LANCASTER, PENNSYLVANIA.

FENCE-POST.

SPECIFICATION forming part of Letters Patent No. 361,880, dated April 26, 1887.

Application filed December 20, 1886. Serial No. 222,104. (No model.)

To all whom it may concern:

Be it known that I, ISRAEL L. LANDIS, a citizen of the United States, residing at Lancaster, in the county of Lancaster and State 5 of Pennsylvania, have invented certain new and useful Improvements in Fence-Posts, of which the following is a specification, reference being had therein to the accompanying drawings.

10 My invention relates to an improvement in fence-rail supports, and in a novel means for connecting to such supports the rails, which will be fully understood from the following description, when taken in connection with 15 the annexed drawings, in which—

Figure 1 is a perspective view of a fence-rail support, showing four rails rigidly secured to it, and indicating the support anchored in the ground. Fig. 2 is a vertical 20 cross-section of the same, indicating the rails when half spliced longitudinally. Figs. 3, 4, 5, and 6 show the clip-braces which I shall employ on the filling or spacing blocks between the rails and the supports.

25 Referring to the annexed drawings by letters, A designates a vertical fence-rail support, and B B designate several horizontal rails which are sustained thereby.

The main object of my invention is to dispense with wood posts, also costly metal posts, 30 and to sustain the fence-rails B by means of a support which is formed of a single wire of a proper gage, which I prefer to galvanize. This support consists, essentially, of a vertical 35 upwardly-tapering portion, formed by looping a single wire, as clearly shown in Figs. 1 and 2 of the annexed drawings, so that its limbs diverge from its connected upper end, a', downward to the angles e e, constituting an 40 open or skeleton wedge. From the angles e e the wire branches outwardly and downwardly, forming obtuse-angular limbs b b, which I shall denominate the "anchor-braces." The termini of these braces are wrapped securely 45 about anchor-blocks d d, buried a sufficient distance in the ground to sustain the fence and prevent upheaval by frost.

The rails B may be united at their ends by the half-lapped splices, or in any other suitable

manner. These splices occur between the 50 limbs of the supports A, and they are rigidly bound together vertically and laterally by means of interposed spacing-blocks E, of equal or of different length, in combination with 55 clasps or clips D, which are in a wedging manner driven down on the upwardly-tapered wire support A, and which may be made of wrought-iron or of malleable cast-iron. These 60 clips or, more properly speaking, binders are constructed with one or more bracing tongues or extensions, F, formed integral with each one of them, which prevents the said spacing-blocks from tilting or otherwise being displaced.

In Fig. 5 I have represented a modification 65 of the block binders shown in Figs. 1, 2, 3, and 4, which consists in using a loop of bent wire, bent and twisted so as to embrace the support A, and also to afford bearing-tongues f f for a spacing-block, E.

In Fig. 6 I show the clip formed of a square 70 plate of metal bent so as to embrace and clasp the two limbs of the support and the spacing-block.

It will be observed from the foregoing that 75 I have practically a tapered skeleton fence-rail post terminated by diverging anchor-braces formed of a single wire; also, that I combine with such a bracing-support fence-rails, spacing-blocks, and bracing and binding clips. 80 When these parts are put together, as shown in Fig. 1, the rails and blocks are all rigidly and securely locked by means of the wedge-key K, driven between the lapped ends of the 85 topmost rails and the upper end of the support a'.

Having described my invention, I claim—

1. In a fence-post, the combination of the support A, anchored in the ground, substantially as described, with the fence-rails B, 90 spacing-blocks E, interposed between the rails and the limbs of the post, and the binding-clips D, embracing the limbs of the post and the spacing-blocks, and provided with tongues F, extending longitudinally of the 95 post and serving to steady and hold the said spacing-blocks in place, substantially as described.

2. In a fence-post, the support A, bent to form an upwardly-tapering open wedge, and having its lower extremities bent outwardly and united to suitable anchor-blocks, in combination with the tie e, the fence-rails, the spacing-blocks, the embracing-clips, and a wedging-key, all arranged substantially as described.

In testimony whereof I affix my signature in presence of two witnesses.

ISRAEL L. LANDIS.
